UNITED STATES PATENT OFFICE.

GEORGE W. DIGHT, OF SEATTLE, WASHINGTON.

PUMPING APPARATUS.

1,279,293.

Specification of Letters Patent. Patented Sept. 17, 1918.

Application filed June 12, 1917. Serial No. 174,389.

To all whom it may concern:

Be it known that I, GEORGE W. DIGHT, a citizen of the United States, residing at Seattle, in the county of King and State of Washington, have invented a new and useful Improvement in Pumping Apparatus, of which the following is a specification.

This invention relates to improvements in pumping apparatus, and to improvements 10 in means for operating the same, and the object of this improvement is to provide a pump of relatively cheap and simple form of construction that is capable of utilizing the power of water under a small head to 15 pump a lesser amount of water to a high elevation.

Further objects are to design a pumping device that may be installed at a comparatively low cost along creeks, rivers and 20 the like where it is desired to pump water to a considerable elevation for irrigation or other purposes.

The invention consists in the novel construction adaptation and combination of 25 parts as will be more clearly hereinafter described and claimed.

In the accompanying drawings Figure 1 is a view in longitudinal cross section of this device showing certain parts in elevation; 30 Fig. 2 is a view in cross section substantially on broken line 2, 2 of Fig. 1; Fig. 3 is a view in cross section of the water wheel and discharge end of the spout or trough for conveying water to the wheel; Fig. 4 is 35 a view in elevation of the wheel shown in Figs. 1 and 4, and Fig. 5 is a view in side elevation of a slightly modified form of the invention.

Referring to the drawings, throughout 40 which like reference numerals indicate like parts the numeral 7 indicates a box or tank that is open at one end and within which this pumping mechanism is disposed, and 45 8 and 9 are pump cylinders disposed within one end of the box 7 and fixedly secured thereto.

10 are pipes that are secured to the pump cylinders and extend upwardly therefrom in axial alignment therewith and 11 are 50 piston rods that extend downwardly through stuffing boxes 12 in caps 13 on the tops of the pipes 11 and are secured at their lower ends to pistons 14 disposed within the cylinders 8 and 9.

55 The pistons 14 are provided with suitable

valves 15 designed to permit water to pass upwardly therethrough, and to prevent water from passing downwardly therethrough and the bottom of the cylinders 8 and 9 are also provided with valves 16 designed to admit water into the cylinders and to prevent water from passing out of such cylinders.

17 are pipes that make connections with the pipes 10 near the tops thereof, as with 65 the caps 13, and extend upwardly to any point at which it is desired to deliver water.

18 is a water wheel that is mounted on a transverse shaft 19 near the outer end of the box 7. The water wheel 18 consists of a 70 plurality of buckets 20 formed and inclosed by walls 21 and each provided with an opening 22 through which water may be received and discharged.

23 is a trough extending lengthwise of 75 the box 7 and having its discharge end located above the wheel 18 and provided with an inclined slot 24 through which water may be delivered into the wheel.

The inlet end of the trough 23 is connected with another trough or water conduit 25 through which water may be carried to and delivered into the trough 23 and the outlet end of the trough 23 is provided with a slideable gate 26 by which the discharge 80 slot 24 may be closed.

28 are lever arms that are pivoted as at 29 to fixed supports 29', and are connected by slot and pin connections 30 with the top 90 ends of the piston rods 11.

The longer ends of the lever arms 28 extend outwardly into close proximity to the sides of the wheel 18 and are slotted as indicated by dotted lines at 31 and 32 Fig. 1.

At the termination of the slots 32 the lever 95 arms 28 are each provided with inclined surfaces 33 and 34 for purposes hereinafter pointed out.

The water wheel 18 is provided on one end with two oppositely directed arms 35 100 that project radially outward beyond the circumference thereof and on the opposite end with two similar outwardly projecting, oppositely disposed, arms 36 that are arranged substantially at right angles to the 105 arms 35.

Upon the ends of each of the arms 35 and 36 are provided outwardly directed pins or rollers 37 that are adapted to engage within the slots 31 and 32 and with the inclined 110

surfaces 33 and 34 and move the outer ends of the lever arms 28 up and down as the water wheel turns.

When the lever 28 is in the position shown by full lines in Fig. 1, the pump piston 14 connected therewith is at its lowest point, and the uppermost roller 37 is just passing onto the inclined surface 33. As such roller moves around in its circumferential path, it will roll over the surfaces 33 and 34 and depress the outer end of the lever arm 28 into substantially the position shown by broken lines, Fig. 1, in which position the lever will remain until the roller 37 on the opposite arm 35 passes upwardly through the slot 31, engages the top of the slot 32 and in its upward movement lifts the outer end of the lever arm into the position shown in full lines.

10 The levers 28 move in opposite directions at the same time so that when one pump cylinder is discharging the piston in the other cylinder is moving downwardly.

15 The levers 28 are each recessed as at 40 to clear the shaft 19.

It will be noted that the outer ends of the lever arms 28 are made relatively heavy to serve as a counterbalance for a portion of the weight of the water on the upward stroke 30 of the pistons.

Fig. 5 shows a modified form of this device wherein the levers 28 are replaced by levers 41 that are connected by slots 42 and pins 43 with crank arms 44 on the water wheel shaft 19.

In ordinary use water is maintained in the box 7 to about the level of the lower side of the wheel 18, as shown in Fig. 1, and such water is drawn into the cylinders 8 and 9 and 40 lifted by the pump pistons 14 in well known manner as the pistons reciprocate.

It is obvious that changes in the precise form of construction of this device may be resorted to within the scope of the appended claims.

What I claim and desire to protect by Letters Patent is:

1. A pumping device of the class described comprising a tank, two pump cylinders located in one end of said tank, pipes extending upwardly from said pump cylinders, pistons, piston rods secured to said pistons and projecting outwardly from the top of said pipes, a water wheel located in the opposite end of said tank, outwardly projecting arms on the ends of said water wheel, rollers on said arms, levers pivoted on said tank and articulated with said pistons the longer ends of said levers being disposed in close proximity to said water wheel and having slots provided therein and inclined surfaces formed thereon that are adapted to be engaged by said rollers to oscillate said lever arms, and means for delivering water to said water wheel.

2. A pumping device of the class described comprising a tank, two pumps located in one end of said tank, a water wheel located in the opposite end of said tank, outwardly projecting arms on the ends of said water wheel, rollers on said arms, levers pivoted on said tank and connected with said pumps, the longer ends of said levers being disposed in close proximity to said water wheel and having slots provided therein and inclined surfaces formed thereon that are adapted to be engaged by said rollers to oscillate said lever arms and means for delivering water to said water wheel.

Signed by me at Seattle, Washington, this 6th day of June, 1917.

GEORGE W. DIGHT.

Copies of this patent may be obtained for five cents each, by addressing the "Commissioner of Patents, Washington, D.C."
